UNITED STATES PATENT OFFICE.

MABRY LOVEJOY, OF CARLSBAD, NEW MEXICO, ASSIGNOR OF ONE-HALF TO JOSHUA D. KUYKENDALL, OF CARLSBAD, NEW MEXICO.

MECHANICAL TOY.

1,068,147.

Specification of Letters Patent.

Patented July 22, 1913.

Application filed May 28, 1912. Serial No. 700,179.

To all whom it may concern:

Be it known that I, MABRY LOVEJOY, a citizen of the United States, and a resident of Carlsbad, in the county of Eddy and State of New Mexico, have invented certain new and useful Improvements in Mechanical Toys, of which the following is a specification, reference being had to the accompanying drawings.

10 This invention relates to certain new and useful improvements in mechanical toys.

The primary object of my invention is to provide an attractive Christmas toy arranged to be secured to a vertical support such as a wall, representing Santa Claus driving a team of deer hitched to a sleigh from the bottom of which stockings or other receptacles are suspended. The sleigh body serves to receive toys, candies and other articles and the receptacles secured below the same may also receive toys, nuts, confectionery, and the like.

Another object is to provide a mechanical toy in the form of a sleigh to which a team of deer are secured with Santa Claus as driver, the deer and the figure of Santa Claus being secured to vibrating members which are given action to impart a rocking movement to the figures.

30 A still further object is to provide a toy, representing Santa Claus upon a sleigh driving a team of deer, which is set in motion by the weight of a star representing the Star of Bethlehem, so that as the star descends the deer and figure of Santa Claus are actuated, the mechanism actuating the figure also actuating certain sound producing members, the deer serving as holders for suitable bells.

40 With these and other objects in view the present invention consists in the combination and arrangement of parts as will be hereinafter more fully described and finally pointed out in the appended claims, it being further understood that changes in the specific structure shown and described may be made within the scope of the claims, without departing from the spirit of the invention.

50 In the accompanying drawings forming a part of this specification, and in which like numerals of reference indicate similar parts in the several views: Figure 1, shows a side elevation of the completed toy. Fig. 2, is

an enlarged sectional view through the 55 sleigh body. Fig. 3, is a detail of the operating shaft. Fig. 4, is a detail of the shaft sleeve. Fig. 5, is a detail of the pawl disk. Fig. 6, is a view on line 6—6 of Fig. 1. Fig. 7, is a detached detail of the rear rocker. 60 Fig. 8, is a detached detail of the forward rocker. Fig. 9, is a detached sectional detail of the rocker support. Fig. 10, shows the position of the steel tone combs with relation to the pick loop. 65

In carrying out the aim of my invention, I provide a receptacle in the form of a sleigh body comprising the front member 20, the bottom 23, the rear or wall member 20', having the supporting loops 19, the 70 front end sections 18, and rear end sections 16. The bottom 23, is also secured to the cross partition 17. As shown in Fig. 2, the bottom 23, is positioned a suitable distance above the lower edge of the front, 75 rear and end members. Held between the members 20 and 20', is the forward section 18', forming the dash of the cutter and a portion of this dash runs below and parallel to the bottom 23, the end sections 18, being secured thereto. Secured to the bottom 23, are the two bearings 24 and 25, and held within the bearing 24, and passing through the slot 21, within the forward end member 18, and extending through an opening within the dash section 18', is the crank shaft 10, a detail of which is shown in Fig. 3. This shaft has secured to it the disk 13, carrying a pawl 14, which is actuated by means of the spring 15, as shown in Fig. 90 5. Secured to the shaft 10, adjacent to the disk 13, is the stop collar 13', the bearing 24, being held between the members 13 and 13', as shown in Fig. 2. The shaft 10, has the intermediately positioned crank 12, the 95 end crank 16, and the pick loop or crank 11.

Passing through an opening within the lower portion of the rear end 16, is the shaft sleeve 26, shown in detail in Fig. 4. This sleeve carries the operating knob 29, which 100 is held upon the outer end at the rear of the cutter as shown in Fig. 2, the knob 29, and the collar 2', preventing lengthwise displacement of this shaft sleeve. At the remaining end the sleeve carries the spool 27, 105 to which is secured the ratchet 28, arranged for co-action with the pawl 14. The shaft sleeve at its inner end is supported within

the bearing 25, as shown in Fig. 2. The inner end of the shaft 10, is partly carried within this sleeve 26.

Secured to the front and wall sections 20 and 20', and the end sections 16 and 18, are the hooks 32, which are arranged to receive the upper ends of stockings or other suitable receptacles.

Secured to the under portion of the bottom 23, are the steel comb teeth 40, shown in Fig. 10, a number of such teeth being used and these teeth are placed in the path of the revolving pick loop 11. Secured to the dash section 18', held below the bottom 23, are similar steel combs, having teeth 40'. These teeth are graduated and are tuned so as to emit a musical sound, when struck by the pick loop 11. Secured to and wound about the drum 27, is a strand 30, having a hook 7, secured to a weight 8, in the form of a star.

Secured to the dash portion 18', by means of the flanges 3, shown in Fig. 1, are two similar side members 2, connected transversely by means of the supporting plate 4, having the securing flanges 5, as shown in Fig. 9. These side members 2, have the openings 39' and 40'. Held within the openings 39', is a pin 36', which carries the rear or main rocker 35, this rocker is in the form of a plate at one end having the ear 51. Near the end carrying the ear 51, the rocker 35, is provided with a plurality of openings 37', within which a screw 35', is removably held. By means of the pin 36', the rocker 35, is pivotally held between the members 2. The member 35, has the upstanding stiffening edge flanges 45, and it is within these flanges that the pin 36' is held. Within the forward end of the rocker 35, is an opening 51' into which is hooked the lower end of the link 50. Near the forward end of this rocker 35, are secured two figures A, representing reindeer, each carrying a bell a. Near the rear the rocker carries the figure C, representing Santa Claus, this figure being secured by means of the screw 35', passing through one of the openings 37'. The figure C, serves also as a counterpoise. As shown in Fig. 2, the rear end of the rocker 35, extends a suitable distance beyond the forward end 18, of the sleigh body. Pivotally held to a pin 43, passing through the side members 2, is the auxiliary rocker 42, having the upstanding flange 42', and to this forward rocking plate are secured two figures B, also representing reindeer, which also carry the bells a. The flanges 42', of this rocker 42, carry a pin 52 which is arranged to pivotally hold the upper end of the link 50, in the manner disclosed in Fig. 1. Hooked within the ear 51, forming a part of the rocker 35, is the link 53 which has its lower end in engagement with the crank 12 of the shaft 10. It is through

this connecting link 53 that the movement of the shaft 10 is imparted to the rockers.

The toy is intended to be secured to a wall or any other suitable vertical support by means of tacks or screws inserted through the supporting ears 19.

If the device is to be used on Christmas eve, stockings supposed to be filled by Santa Claus, are suspended from the hooks 32. In lieu of the stockings, cornucopias or other containers may be used.

In order to set the device in operation the sleeve 26, is rotated by means of the operating knob 29, so that the strand 30, is wound upon the drum 27. In the winding operation of the strand the ratchet works under the pawl. As soon as the shaft 26, is released to bring into play the weight or gravity of the star 8, the ratchet 28, engages the pawl 14, and results in rotating the shaft 10. As this shaft rotates the pick loop 11, contacts with the combs and causes a musical sound. At the same time the crank 12, actuates the link 53, resulting in the plate 35, being rocked or vibrated upon its pivotal support 36'. This rocker 35, however, by means of the link 50, is connected to the forward rocker 42, so that a rocking movement is simultaneously imparted to this forward member 42. By virtue of the connecting link 50, as the forward end of the main or rear rocker 35, rises, the rear end of the plate 42, is also made to rise so that the figures of the deer are given an alternate movement, that is, as the heads of the forward deer rise, the heads of the rear deer fall. As the rocker 35, is actuated, the figure of Santa Claus has also imparted to it an up and down movement. It is this rocking movement of the figures A and B, that causes the ringing of the bells a.

If it should be desired to operate the device without the weight 8, the operator simply actuates the shaft 10, by means of the hand crank 16, which is positioned immediately in front of the dash section 18'.

The front and end panels may be embellished by means of suitable legends and the whole toy is of course appropriately colored. The members 2, may have their upper edges serrated or scalloped to represent a snow ridge over which the deer are passing.

Having thus described my said invention, what I claim as new and desire to secure by United States Letters Patent is:

1. In combination, a receptacle, a crank shaft ending in an operating handle carried by said receptacle, a supporting plate extending from one end of said receptacle, a rocker plate pivotally secured to said supporting plate, and a connecting rod extending from said crank to said rocker plate.

2. In combination, a receptacle, a crank shaft ending in an operating handle revolvably secured to said receptacle, a supporting

plate extending from one end of said receptacle, a rocker plate pivotally secured to said supporting plate, a connecting rod extending from said crank to said rocker plate, and the figure of a deer secured to said rocker plate.

3. In combination, a receptacle, a crank shaft ending in an operating handle carried by said receptacle, a supporting plate extending from one end of said receptacle, a rocker plate pivotally secured to said supporting plate, a connecting rod extending from said crank to said rocker plate, the figure of a deer secured near one end of said rocker plate, and the figure of Santa Claus adjustably secured to the remaining end of said rocker plate.

4. In combination, a receptacle, a crank shaft ending in an operating handle carried by said receptacle, a supporting plate extending from one end of said receptacle, a rocker plate pivotally secured to said supporting plate, a connecting rod extending from said crank to said rocker plate, said crank shaft having an intermediately positioned loop, an ornamental figure secured to said rocker plate, and a tone comb in the path of said loop.

5. In combination, a receptacle, a crank shaft ending in an operating handle and having an intermediately positioned pick loop carried by said receptacle, a supporting plate extending from one end of said receptacle, a rocker plate pivotally secured to said supporting plate, a connecting rod extending from said crank to said rocker plate, the figure of an animal secured to said rocker plate near one end, the figure of Santa Claus secured to said rocker plate near the opposite end, and a tone comb in the path of said pick loop.

6. In combination, a receptacle, a crank shaft ending in an operating handle carried by said receptacle, a supporting plate extending from one end of said receptacle, a rocker plate pivotally secured to said supporting plate near one end, a connecting rod extending from said crank to said rocker plate, a second rocker plate pivotally secured to said supporting plate near the remaining end, a bar connecting said two rocker plates, the figure of a reindeer secured to each of said rocker plates.

7. In combination, a receptacle, a crank shaft ending in an operating handle carried by said receptacle, a supporting plate extending from one end of said receptacle, a rocker plate pivotally secured to said supporting plate near one end, a second rocker plate pivotally secured to said supporting plate near the remaining end, a rod connecting said two rocker plates, the figure of a reindeer secured to each of said rocker plates, the figure of Santa Claus adjustably secured to said first mentioned rocker plate, and a

connecting rod extending from said first mentioned rocker plate to said crank shaft.

8. In combination, a receptacle, a crank shaft ending in an operating handle carried by said receptacle, a supporting plate extending from one end of said receptacle, a main rocker plate pivotally secured to said supporting plate at the end nearest said receptacle, an auxiliary rocker plate pivotally secured to said supporting plate at the opposite end, a rod connecting said rocker plates, the figure of a reindeer secured to both the said rocker plates, the figure of Santa Claus secured to said main rocker plate, and a connecting rod extending from said main rocker plate to said crank shaft.

9. The combination with a receptacle of a crank shaft ending in an operating handle, a supporting plate extending from one end of said receptacle, a main rocker plate secured to said supporting plate at the end nearest said receptacle, an auxiliary rocker plate pivotally secured to said supporting plate at the remaining end, a rod connecting said two rocker plates, the figure of a reindeer secured to each of said rocker plates, the figure of Santa Claus adjustably secured to the end of said main rocker plate, a rod extending from the crank of said shaft to said main rocker plate, said shaft having a pick loop, and a tone comb secured to said receptacle in the path of said pick loop.

10. In combination, a receptacle in outline representing a sled, a crank shaft ending in an operating handle carried by said receptacle, a supporting plate extending from the forward end of said receptacle, a main rocker plate pivotally secured to said supporting plate and extending over the forward end of said receptacle, the figure of Santa Claus adjustably secured to the projecting end of said main rocker plate, an auxiliary rocker plate pivotally secured to said supporting plate, a rod connecting said two rocker plates, the image of a reindeer secured to each of said rocker plates, said shaft having a pick loop, a connecting rod extending from said crank to said main rocker plate, and a tone comb in the path of said pick loop.

11. In combination, a receptacle, a crank shaft carried by said receptacle, a sleeve engaging said shaft, a drum secured to said sleeve, a ratchet wheel secured to said drum, an operating knob secured to said sleeve, a spring actuated pawl secured to said crank shaft, a supporting plate extending from one end of said receptacle, a rocker plate pivotally secured to said supporting plate, a rod connecting said crank shaft to said rocker plate, and a weight carrying strand wound upon said drum.

12. In combination, a receptacle, in the form of a sled, a crank shaft carried by said receptacle, a spring actuated pawl carried

by said crank shaft, a sleeve working upon said shaft, an operating knob secured to said sleeve, a drum secured to said sleeve, a ratchet secured to said drum for co-action with said pawl, a weight carrying strand wound about said drum, an outstanding supporting plate secured to one end of said receptacle, a rocker plate pivotally secured to said supporting plate, the image of a reindeer secured to said rocker plate, the image of Santa Claus secured to said rocker plate, and a connecting rod extending from said crank shaft to said rocker plate.

13. In combination, a receptacle in outline resembling a sled, a supporting plate extending from one end of said receptacle, a rocker plate pivotally secured to said supporting plate, the image of a reindeer secured to said rocker plate near one end, the image of Santa Claus adjustably secured to said rocker plate near the opposite end, a crank shaft secured to said receptacle having a pick loop, a rod extending from said crank and secured to said rocker plate, a spring actuated pawl carried by said shaft, a drum, means to support said drum, a ratchet carried by said drum for co-action with said pawl, a weighted strand wound about said drum, and a tone comb in the path of said loop.

14. In combination, a receptacle in outline resembling a sled, a supporting plate extending from one end of said receptacle, a main rocker plate pivotally secured to said supporting plate and having one end projecting over said sled, the image of Santa Claus secured to said projecting end, the figure of a reindeer secured to said rocker plate near the remaining end, an auxiliary rocker plate pivotally secured to said supporting plate in advance of said first men-

tioned rocker plate, a reindeer secured to said auxiliary rocker plate, a rod connecting said rocker plates, a crank shaft, a rod connecting said crank shaft to said main 45 rocker plate, a spring actuated pawl carried by said crank shaft, a sleeve engaging said shaft having an operating knob, a drum secured to said sleeve, a ratchet secured to said drum for co-action with said pawl, a strand 50 wound upon said drum, and a weight carried by said strand.

15. The combination with a receptacle in outline resembling a sled, of a supporting plate extending from one end of said receptacle, a main rocker plate pivotally secured to said supporting plate having one end projecting over said receptacle, the figure of Santa Claus secured to said projecting end, the figure of a reindeer secured to said rocker plate, an auxiliary rocker plate in advance of said main rocker plate pivotally secured to said supporting plate, the figure of a reindeer secured to said last mentioned rocker plate, a rod connecting said two rocker plates, a crank shaft having a pick loop carried by said receptacle, a tone comb in the path of said pick loop, a spring actuated pawl carried by said shaft, a sleeve in engagement with said shaft having an 60 operating knob, a drum secured to said sleeve, a ratchet secured to said drum for co-action with said pawl, a strand wound upon said drum, and a weight carried by 65 said strand.

In testimony whereof I affix my signature, in presence of two witnesses.

MABRY LOVEJOY.
